EX

DESIGN.

—o—
G. S. BARKENTIN.
HINGE.

No. 19,444.

Patented Nov. 26. 1889.

UNITED STATES PATENT OFFICE.

GEORGE S. BARKENTIN, OF NEW BRITAIN, CONNECTICUT, ASSIGNOR TO
P. & F. CORBIN, OF SAME PLACE.

DESIGN FOR A HINGE.

SPECIFICATION forming part of Design No. 19,444, dated November 26, 1889.

Application filed October 30, 1889. Serial No. 328,709. Term of patent 7 years.

To all whom it may concern:

Be it known that I, GEORGE S. BARKENTIN, a citizen of the United States, residing at New Britain, in the county of Hartford and State of Connecticut, have invented and produced a new and original Design for a Hinge, of which the following is a specification, reference being had to the accompanying drawing, forming part thereof, in which the only figure is a face view of the hinge, showing my design.

The leading feature of my design consists in the surface ornamentation of the panels by conventional leaves and rosettes of leaves, each having a bead-like ornament extending over the mid-rib.

a designates the rosettes composed of leaves or leaflets, and *b* the scroll-like leaves extending from the middle portion of each hinge-leaf upwardly and downwardly, all having a row of bead-like ornaments *c* extending along their mid-ribs, as shown. The panel of each hinge-leaf is bordered by a concave molding

or cove *d*, surrounding which is a border of beads *f*, sunk in the surface of the plain border *g*.

What I claim is—

1. The design for the surface ornamentation of a hinge herein shown and described, the same comprising the leaves and rosettes of leaflets having beads extending along their mid-ribs, and a raised surrounding border having the border beads in its face, as set forth.

2. In a design for the surface ornamentation of a hinge herein shown and described, the surface ornamentation of the panels comprising the rosettes of leaflets and the scroll-leaves having the rows of bead-like ornaments extending along their mid-ribs, as set forth.

GEORGE S. BARKENTIN.
